COMMUNICATION SYSTEM

Alfred Wiessner, Berlin, Germany, assignor to
 C. Lorenz Aktiengesellschaft, Berlin-Tempelhof,
 Germany, a company

Application June 9, 1938, Serial No. 212,665
 In Germany June 15, 1937

2 Claims. (Cl. 179—91)

The present invention relates to communication systems, and more specifically to wire-radio systems operating with carrier frequency intelligence transmission over telephone lines.

5 It is a known expedient to connect the incoming and outgoing lines of a telephone exchange office to main distributing devices thereof. Such devices comprise a plurality of terminal strips arranged in racks or frames and serve for inter-
 10 connecting the incoming lines and the leads pertaining to the further circuit elements and switching means of the exchange office.

Certain difficulties have been experienced in connection with the recently generalized simultaneous utilization of telephone system subscriber lines for high frequency current transmission, such as wire-radio, alarming and the like, and these difficulties are particularly introduced on account of restricted space conditions and the 20 great number of wirings required for the necessary interconnections.

Propositions have been made in the past to apply the high frequency oscillations to the selector equipments of such exchanges and to 25 provide the electric separating filters either in the selector racks or in particular racks or frames adapted for this purpose, but this expedient requires a great number of interconnections in addition to the low frequency lines allotted 30 ready present in the system. The invention has for its object to avoid these disadvantages. This is accomplished according to the present invention by so arranging the high frequency portion that the high frequency oscillations which are 35 to be applied to the outgoing subscriber lines of a telephone system are impressed upon these lines in the main distributing devices and utilizing the terminal strips of such main distributing devices in a manner which permits the high frequency oscillations to be duly impressed with a 40 minimum expenditure of additional connections.

The invention will be more readily understood from the following description taken in conjunction with the accompanying drawing, in 45 which

Fig. 1 is a perspective view of a main distributor rack or frame, Fig. 2 illustrates a partially sectioned side elevation of one embodiment of a terminal strip according to the invention, Fig. 3 is a front elevation of the terminal strip shown in Fig. 2, while Fig. 4 is a top view of the same terminal strip.

Referring to Fig. 1, V denotes the main distributor rack or frame which is adapted to re-

ceive a plurality of terminal strips L more precisely shown in the Figs. 2 to 4.

A terminal strip according to the present invention is shown in the Figs. 2 to 4 and comprises a base plate 1 carrying at its rear a box 2 enclosing the circuit elements, i. e. inductances and capacities, of the electric separating filters allotted to the individual lines. The front of the base plate 1 carries two bars or ribs 3 and 4 of insulation, each of which is provided with three arrays of soldering tabs 5, 6, 7 and 8, 9, 10, respectively. For instance, the subscriber lines may be connected to the soldering tabs of the arrays 5, 6 and 7, while the tabs of the arrays 8, 9 and 10 are connected to the leads pertaining to the exchange equipment. Each of said arrays generally comprises twenty soldering tabs. A covering plate or disc 11 is attached to the upper ends of said bars and serves as support for soldering tabs over which the high frequency currents are impressed upon the system. One of the soldering tabs 12 of this plate is allotted to each three-wire group of subscriber lines terminated at the soldering tabs of the bar 3. The high frequency currents are applied to the terminal strip 25 over soldering tabs 13 interconnected in groups by conductors 14 as shown in Fig. 3, and each of said groups is fed by high frequency currents of different amplitudes. In cases that it is desired to supply a pair of wires with specific high 30 frequency currents accommodated to the length of said wire lines, a short connection is established between the appertaining soldering tab of array 12 and the conductor 14 conducting the high frequency current of corresponding amplitude. Such short connection is indicated at 35 of Fig. 3.

The electric separating filters arranged in the box 2 are then to be wired in such manner that the low frequency input circuit of the filter is connected to the inwardly projecting part of the soldering tabs which are associated with the incoming leads, that the high frequency input circuit of the corresponding filter is connected to the appertaining soldering tabs of the array 12, and that the output circuit of the filter is connected to the inwardly projecting parts of the soldering tabs allotted to the outgoing leads. The device is also provided with the usual voltage cut-out equipments. The soldering tabs may be 50 fixed in the bars 3 and 4 during the moulding process thereof.

The arrangement according to the invention heretofore described involves the advantage that a very low number of connections is required 55

and, moreover, that electric separating filters may be added to existing distributing devices without any further expenditures.

What is claimed is:

- 5 1. In a communication system, a telephone exchange comprising telephone lines, exchange equipments, main distributing devices, electric separating filters, circuit connections conducting high frequency oscillations adapted to be applied
10 to said lines, and terminal strips comprising a base plate, means for supporting said filters on the rear of said base plate, two extended bars of insulation, and soldering tabs arranged in
- arrays in said bars, and adapted to interconnect said lines, equipments, filters and circuit connections, the soldering tabs of one bar being connected to the separating filter input side and the soldering tabs of the other bar to the separating filter output side. 5
2. In a communication system a telephone exchange as defined in claim 1, having a covering plate fixed on said bars, and soldering tabs in said plate for applying high frequency 10 oscillations.

ALFRED WIESSNER.
